COIN SELECTOR

John Gottfried, Bridgeport, Conn.

Application July 20, 1934, Serial No. 736,179

4 Claims. (Cl. 194—101)

This invention relates to coin selectors, and contemplates a small and compact selector of improved efficiency and capacity for discriminating between genuine coins and slugs having properties so similar to genuine coins that the separation of the two is not effected by ordinary selectors.

A method of coin selection which has been utilized to a limited extent comprises the use of a magnetic field of substantial intensity. It is a familiar principle of electrodynamics that when any object is moved through a magnetic field currents are generated within the moving object, which currents have a magnetic effect tending to oppose the motion which produces them. The intensity of the currents generated in the moving object and the consequent retarding of its movement are proportional to its electrical conductivity. Thus, the bodies of copper and aluminum, which are good electrical conductors, are more retarded than bodies of coin silver (the customary silver coinage alloy), which has a less conductivity, and objects of the common alloys and of nickel, which are quite indifferently conductive, will be retarded still less. Advantage has been taken of this principle for the purpose of effecting the separation of genuine coins, such as those of coin silver, from coins of other materials and from slugs. In general, however, these devices have been too large and cumbersome for practical use. One difficulty is that almost invariably three paths are provided for coins or slugs passing through the magnetic field according to the amount of their retardation in the magnetic field. The provision of two or more outlet passages for rejected coins and slugs adds to the size and complexity of the apparatus. Moreover, the difference in the electrical properties of genuine coins and certain slugs is so slight that their paths of movement on leaving the magnetic field may vary but slightly. In general, prior devices have not been of sufficient accuracy and discrimination to effect a positive separation.

It is an object of this invention to provide a magnetic field of increased local intensity, thereby increasing the difference in the subsequent path of movement of genuine coins and other objects having properties but slightly different from those of genuine coins.

It is a further object of the invention to provide passages for coins and other articles leaving the magnetic field so designed as to effect an accurate separation between genuine coins and

slugs differing only very slightly from genuine coins.

With these and other objects in view, the invention consists in the novel combinations and arrangements of parts, one embodiment of which has been illustrated in the accompanying drawing, in which:

Fig. 1 is a side elevation, partly in section, of a coin selector, including one embodiment of the present invention.

Fig. 2 is a vertical section on the line 2—2 of Fig. 1.

Fig. 3 is an enlarged detail of a magnet pole piece.

The selector may comprise side plates 10 and 11, between which side plates are secured members 12 and 13 defining a coin passage 14. Adjacent the entrance to the coin passage 14 may be secured a conventional type of coin receiving slot and passage, indicated generally by the numeral 15, which may be provided with a small magnet 16 for preventing the passage of slugs of magnetic material. The coin chute defining member 12 terminates adjacent a pole piece 17 of a strong magnet 18, while the opposite wall of the passage comprises a vertically extending member or wall 19 which may be integral with member 13 and is separated from the end of member 12 by a distance substantially greater than the diameter of a coin. This widening of the coin passage is to permit the divergence in the paths of genuine and spurious coins which is initiated by their passage through the magnetic field between the pole pieces 17. The pole pieces 17 are of a special construction, forming one feature of the present invention which may be described as follows:

Inside each pole of the magnet 18 is a cylindrical pole piece 17 provided at its inner or free end with a projection 20 of reduced diameter which is received in an aperture in one of the side plates 10 and 11. The projections 20, however, are not cylindrical, but are provided with lateral V-shaped extensions or points 21, the side plate apertures being shaped accordingly. Thus, the magnetic field in the coin chute between the pole faces is not the usual symmetrical field passing between poles of circular configuration, instead, due to the concentration of magnetic flux at the points 21, an intense local field between these points is created. The motion retarding currents generated in conductive objects moving through this field are proportionately intensified, and a wider divergence in their subsequent paths due to differences in their conductivity is secured.

Below the widened coin passage defined by the end of the member 12 and the downward extension 19 of member 13 is a coin passage dividing member 22 comprising reversely sloping faces 24 and 25 meeting in an upwardly facing edge or point 23. The face 24 defines one side of a passage for accepted coins, while the face 25 constitutes a part of a passage for rejected coins. Preferably, means, such as a slot 26 are provided for adjusting the position of member 22. By the use of the edged member 22 there is secured a very accurate separation of coins whose electrical properties are so similar that passage through the magnetic field causes but slight divergence in their paths of movement. The edge 23 is engaged by the lower portion of the rim of the descending coin and a very slight difference in the lateral position of the coin at the time of this engagement will determine whether it is accepted or rejected. Fig. 1 illustrates in broken line a coin which has descended to contact edge 23 with its center of gravity very slightly to the right of said edge. This coin will be accepted, whereas one contacting edge 23 with its center of gravity but slightly to the left would be rejected.

In operation, coins or slugs of highly conductive materials, such as aluminum and copper, are strongly deflected by passage through the magnetic field between the pole faces 21 and fall somewhat to the left (Fig. 1) of the edge 23, passing down the face 25 to a rejected coin receptacle or outlet. Coins having the electrical properties for which the particular apparatus is designed, such as those of coin silver, will be somewhat deflected or retarded on passing the magnetic field and engage the surface 24 or the edge 23 in such position as to be directed into a chute or receptacle for accepted coins. Coins or slugs of lesser conductivity will be affected still less by passage through the magnetic field and will move into contact with the passage defining member 19 by which they are directed downwardly and caused to engage the point 23 with their center of gravity on the left (Fig. 1) of said point so that they are rejected. Their exit, however, is through the same coin passage as that of coins having an excessive conductivity, and the usual second passage for rejected coins is eliminated. It will be noted that the separator member 22 is so positioned with respect to the passage wall 19 that coins descending along wall 19 engage the separator with their center of gravity to the left of the point 23 and are rejected. Thus, inert and inelastic slugs of low conductivity are directed to the same exit as slugs of high elasticity or high conductivity. A correct coin does not contact wall 19 at all, being deflected in the magnetic field just enough to pass between the lower end of said wall and the surface 24 of the separator. This arrangement, particularly in conjunction with the non-symmetrical magnetic field and/or the pointed separator or passage defining member 22, results in a remarkably delicate discrimination between coins of very similar properties.

In the appended claims the term "coins" iden-

tifies genuine coins, spurious, worn or improper coins or slugs simulating coins, and the term "genuine coins" identifies true coins of the particular size and material which the selector is designed to accept.

The embodiment of the invention illustrated in the drawing and described herein is to be understood as typical and representative only, the invention being susceptible to many modifications, all falling within the scope of the appended claims, which claims are to be broadly construed.

What is claimed is:

1. In a coin selector, in combination, a coin passage, a coin separating magnet adjacent said passage, the pole faces of said magnet extending toward the sides of said coin passage and being provided with lateral projections of small area extending substantially parallel to the walls of said coin passage, whereby magnetic flux in said coin passage is concentrated between said projections.

2. In a coin selector, in combination, a coin passage, a coin separating magnet adjacent said passage, the pole faces of said magnet extending toward the sides of said coin passage and being provided with pointed lateral projections extending substantially parallel to the walls of said coin passage, thereby creating a high concentration of magnetic flux in said coin passage between the points of said projections and a lesser flux between other parts of said pole faces.

3. In a coin selector, in combination, a magnet adapted to affect the travel of passing coins in a manner and to an extent dependent upon their electrical conductivity, a coin passage directing coins between the poles of said magnet, a widened coin passage beyond said magnet permitting divergence in the paths of movement of coins passing said magnet, a marginal wall defining one side of said widened passage and guiding coins receiving a minimum of deflection by said magnet, a separator in said widened coin passage comprising reversely sloping faces and an upstanding edge adapted for engagement by the rims of descending coins, an outlet for genuine coins defined by one face of said separator and the end of said marginal wall, and an exit for all classes of spurious coins defined by the opposite face of said separator.

4. A coin selector comprising a continuous coin passage having a width substantially equal to the thickness of a genuine coin, an outlet for genuine coins and one outlet for all spurious coins, both outlets being in the plane of said passage, a magnet having pole faces with laterally projecting points forming parts of the walls of said coin passage and adapted to create an intense local magnetic field therein, an edged separator in said passage having reversely sloping faces directing coins to said outlets, and means for guiding coins of deficient conductivity to engage said separator in such a manner as to be directed toward the same outlet as coins of excessive conductivity.
